UNITED STATES PATENT OFFICE

HAROLD L. LYON, OF HONOLULU, TERRITORY OF HAWAII

RECORDING RADIOMETER

Application filed July 25, 1930. Serial No. 470,756.

My invention relates to improvements in radiometers whereby the movement of a light receiving element may be used to record the amount of sunlight received upon the element.

An object of the present invention is to provide a simple device which is positive in action and which will record the amount of sunlight received with sufficient accuracy as 10 to make the device very useful.

A further object is to provide a device of the type described which while being sufficiently accurate for the purpose, is simple in construction and relatively inexpensive 15 to make.

My invention is illustrated in the accompanying drawings forming a part of this application, in which:

Figure 1 is a side elevation of one embodiment of the invention;

Figure 2 is a section on line 2-2 of Figure 1;

Figure 3 is a section on line 3-3 of Figure 1 having in addition thereto a diagrammatical recording circuit;

Figure 4 is a side elevation of a modified form of the device;

Figure 5 is a section on line 5-5 of Figure 4; and

Figure 6 is a section on line 6-6 of Figure 4, with the addition of a diagrammatical recording circuit.

In carrying out my invention I make use of what is known as a "Franklin's pulse-glass", or a modification thereof. This consists of a hermetically-sealed container from which the air has been exhausted and which contains a volatile liquid, such as alcohol or ether together with the vapor thereof.

In Figure 1 I have shown a bulb 1, which is preferably blackened in order to absorb a maximum amount of heat or radiant energy. A similar bulb 2 is connected to the bulb 1 by means of the tube 3.

In Figure 1 I have shown the tube 3 as mounted on a block 4 by means of straps or yokes 5. The block 4 is pivotally mounted on an axle 6 in brackets 7 carried by the base 8. One end of the axle 6 is prolonged 50 and secured thereto is an L-shaped arm 9.

Secured to the base 8 is a back portion 10 which supports the top 11 to which a depending portion 12 is secured (see Figure 3). A pair of flexible contacts 13 is carried by an insulating bracket 14. One of 55 these contacts is connected with a battery B and the other with the coils of a magnet M. The armature A of this magnet is provided with a stylus S arranged to engage a tape T which may be moved in any suitable manner as by clock-work (not shown).

From the foregoing description of the various parts of the device, the operation thereof may be readily understood. Let us assume that the device is placed so that one 65 of the bulbs, preferably the bulb 1, in Figure 1, is below the edge of the member 12 which acts as a shade for the bulb 2 and is in direct sunlight. In Figure 1 I have shown the liquid as partly filling the bulb 70 1 while the bulb 2 is empty. Now, when the bulb 1 is heated up by the sunlight it will force the liquid through the tube 3 and into the bulb 2. The right hand end of the block 4 will then have a greater pressure 75 on it and it will move into the dotted line position shown in Figure 1 until the block 4 engages the stop member 15.

The bulb 2 is now in the sunlight and the bulb 1 is in the shade. The liquid in the 80 bulb 2 will be heated and will be projected into the bulb 1 which is now comparatively cool and this will tilt the device into its original position where the block 4 will rest against the stop 16. This action will continue as long as the apparatus is in position 85 where the bulbs can be affected by the sunlight.

If the radiant energy reaching the bulb is considerable, the time taken to heat the 90 bulb will be less and hence the oscillations will be more frequent.

At each movement, the circuit is closed through the magnet M by the arm 9 short circuiting the contacts 13, since each time 95 the block swings this arm will wipe these contacts and due to their elasticity the contacts will give to permit the passage of the arm. It will be evident that the tape will record the number of oscillations or 100

movements and if the tape is driven by the ordinary clockwork an exact indication of the movements for a given period of time can be made.

5 In Figure 4 I have shown a modified form of the device. This consists of a housing 17, and within this housing is mounted, for revolution, a block 18 on an axle 19. In the present instance there are four bulbs 10 arranged in pairs, the bulbs 20 and 21 being connected by a tube 22 and the bulbs 23 and 24 being connected by a tube 25. In this instance those bulbs outside of the housing are receiving sunlight and when heated 15 to a sufficient degree will force the liquid therein to the bulbs within the housing, the latter being protected by the housing and being cooler. The result is that the bulbs within the housing always have a greater 20 quantity of liquid and therefore tend to rotate the block thus bringing the bulbs with the liquid again under the sunlight when the operation is repeated. The rapidity with which the wheel which is constituted 25 by the bulbs, their connecting tubes and the block, is rotated, depends upon the amount of sunlight coming to the bulbs in any given time.

The axle 19 is prolonged and bears at its 30 end a wiper 26 which will close the contacts 27 and actuate the magnet M to cause the armature A to engage the tape T in the manner already described. The opposite end of the axle 19 is also prolonged and 35 bears a pulley 28 which may be used for the purpose of driving any light mechanism that is desired to operate. Thus the heat of the sunlight may be transformed into mechanical energy.

40 While I have described this device as being used in connection with the recording of sunlight, it will be understood that it can be used in connection with the recording of any radiant energy coming to the 45 receivers which is capable of heating the receivers thus it may be used as a measuring device for heat as well as light.

I claim:

50 1. A radiometer comprising a pair of bulbs, a tube connecting said bulbs and containing a volatile liquid, means for mounting the tube for oscillation about an axis at right angles to the tube, a housing for shading the bulbs from sunlight during a portion of the 55 oscillation, and means for recording the number of oscillations.

50 2. A radiometer comprising a pair of bulbs, a tube connecting said bulbs and containing a volatile liquid, means for mounting the tube for oscillation about an axis at right angles to the tube, a housing for shading either of said bulbs when the other bulb is exposed to sunlight, and means for recording the number of oscillations.

65 3. A radiometer comprising a pair of

bulbs, a tube connecting said bulbs and containing a volatile liquid, means for mounting the tube for oscillation about an axis at right angles to the tube, a housing having a depending shading member for shading either of said bulbs from sunlight when the other is exposed to the sunlight, a pair of contacts carried by the housing, an arm secured to the shaft for closing and opening said contacts, and means for recording the closing and opening of the contacts.

4. A device for measuring the amount of sunshine comprising a pair of bulbs, a tube connecting said bulbs and containing a volatile liquid, means for mounting the tube for oscillation about an axis at right angles to the tube, a housing having a depending shade member for shading either of said bulbs from sunlight when the other is exposed to sunlight, a pair of contacts carried by the housing, an arm secured to the shaft for closing and opening said contacts, a magnet in circuit with said contacts, a stylus actuated by the magnet, and a tape for receiving marks made by the stylus.
